UNITED STATES PATENT OFFICE.

WALTER S. JEWELL, OF PHILADELPHIA, PENNSYLVANIA.

ASSORTING-FILE FOR CHECKS, &c.

SPECIFICATION forming part of Letters Patent No. 744,350, dated November 17, 1903.

Application filed February 5, 1903. Serial No. 142,046. (No model.)

To all whom it may concern:

Be it known that I, WALTER S. JEWELL, a citizen of the United States, residing in the city of Philadelphia, county of Philadelphia, State of Pennsylvania, have invented certain new and useful Improvements in Assorting-Files for Checks, &c., of which the following is a specification.

My invention relates to an improved device 10 designed particularly to facilitate the assorting of bank-checks or deposit-slips, the main object being to provide for effecting such assortment or alphabetical grouping in the act of filing the checks or slips as received, thereby 15 saving most of the time ordinarily required at the end of each day to assort promiscuously-filed checks or slips.

The invention is fully described in connection with the accompanying drawings and 20 the novel features thereof are pointed out in the claims.

Figure 1 is a plan view of my improved assorting-file, the position of two groups of inserted checks being indicated by dotted lines. 25 Fig. 2 is a longitudinal section taken on the line $\alpha\alpha$ of Fig. 1. Fig. 3 is a separate view of one of the leaves drawn to reduced scale, the dotted lines indicating the extended adjacent leaf.

30 The device comprises a series of leaves of uniform width but varying lengths piled upon each other with their similar ends set even, as indicated at 1, Fig. 2, and suitably bound together at said ends, with a bottom cover or 35 board 2 and a top cover 3 of reduced length, as hereinafter described, and with spacing-strips 4 to provide proper room between adjacent leaves for the inserted checks 55. The bottom cover 2 is preferably made of a con- 40 tinuous piece of stiff cardboard and the top cover 3 of less rigid material, though stiffer than the leaves, projected beyond the bound ends only a distance approximately equal to the width of the checks or slips intended to 45 be filed in the device. The successive leaves between these covers are distinguished by the two index characters upon the lapping outer ends of each. Thus, the shortest leaf "A M" projects only slightly beyond the free edge of 50 the adjacent top cover 3, the next lower one "B M" extends slightly beyond "A M," and so on, the free end of each being thus readily

seized to raise the same for inserting the slip. After insertion the latter is pushed back under the cover 3 in its proper compartment, with 55 its outer end projecting, so as to permit of the whole bundle thus grouped by successive insertions being grasped and removed together in proper alphabetical order at the end of the day.

It will be noticed that between each two leaves is formed a double compartment or receiving-space, as shown, the slips grouped under the index-letters "A" to "L" projecting beyond the corresponding edge of the file 65 and those grouped under index-letters "M" to "Z" projecting beyond the opposite edge, while both groups extend inward somewhat short of the center line $\alpha\alpha$ of the device. After they have been separately withdrawn from 70 the file the group "A" to "L" may be placed on top of the group "M" to "Z" and all will be in proper order. To enable the slips to be more conveniently inserted in their proper compartments on either side of the file, the 75 intermediate portion of each leaf is preferably cut back, as shown at 6, thus separating the underlapping index portions 77 of each leaf.

The device shown and described is very 80 simple both in construction and operation; but its use effects a considerable saving of time and labor. It may evidently be modified in detail without departing from the spirit of the invention.

What I claim is—

1. An assorting-file for bank-checks or the like consisting of a stiff bottom cover, a series of flexible leaves of uniform width and uniformly-decreasing length evenly arranged at 90 one end between said covers, spacing-strips between said evenly-arranged ends of the leaves, a stiff top cover of reduced length rigidly bound at one end to said evenly-arranged ends of the bottom cover and of the 95 interposed leaves, said bottom and top covers being rigidly retained in approximately parallel positions and the free index ends of the interposed leaves being flexibly retained in approximately parallel position therewith 100 substantially as set forth.

2. An assorting-file for bank-checks or the like consisting of a stiff bottom cover, a series of flexible leaves of uniform width and uni-

formly-decreasing length evenly arranged at one end between said covers, and having their lapping opposite ends provided with index characters placed adjacent to their side edges 5 and an intermediate portion of each leaf cut back to a reduced length, spacing-strips between said evenly-arranged ends of the leaves, a stiff top cover of reduced length rigidly bound at one end to said evenly-arranged ends 10 of the bottom cover and of the interposed leaves, said bottom and top covers being rig-

idly retained in approximately parallel positions and the free index ends of the interposed leaves being flexibly retained in approximately parallel position therewith substantially as set forth. 15

In testimony whereof I affix my signature in the presence of two witnesses.

WALTER S. JEWELL.
